UNITED STATES PATENT OFFICE.

FREDERICK E. TURNER, OF KANSAS CITY, MISSOURI.

CONTROLLING MECHANISM FOR ELEVATORS.

No. 911,184.

Specification of Letters Patent.

Patented Feb. 2, 1909.

Application filed August 24, 1907. Serial No. 390,053.

To all whom it may concern:

Be it known that I, FREDERICK E. TURNER, a citizen of the United States, residing at Kansas City, in the county of Jackson and 5 State of Missouri, have invented certain new and useful Improvements in Controlling Mechanism for Elevators, of which the following is a specification.

This invention relates to controlling mechanism for elevators, and more especially for drum-operated elevators, and my object is to produce mechanical means for automatically arresting a car in the event that it attains a predetermined limit in its upward or downward travel, without returning the lever or hand-gear in the car to its neutral position and without interfering with the operation of such lever or hand-gear by the operator for the purpose of causing the car to be moved 20 downward or upward respectively.

Heretofore two well known mechanical controlling means have been employed for arresting elevator cars at predetermined points, one of such means being unsatisfactory in 25 that the return of the lever or hand-gear to neutral position is absolutely essential, and to accomplish this the relatively overpowering leverage of such lever or hand-gear has to be overcome by the controlling means, this 30 difficulty being augmented or rendered insurmountable in the event that the operator through fright or otherwise maintains an opposing pressure on the lever or hand-gear.

The other means is unsatisfactory because it 35 involves the use of an independent or separate switch, which when thrown out by the controlling means prevents the further operation of the car in either direction until the said switch is manually returned to its inoperative position.

With the object named in view, the invention consists in certain novel and peculiar features of construction and organization as hereinafter described and claimed; and in 45 order that it may be fully understood reference is to be had to the accompanying drawings, in which—

Figure 1, is a side elevation of an electrically operated drum-mechanism equipped 50 with controlling devices embodying my invention. Fig. 2, is an end view of the same and also shows a portion of the car and the cables connecting the same with the controlling mechanism. Fig. 3, is a top plan view 55 of a part of the drum-mechanism and the controlling mechanism. Fig. 4, is a vertical sec-

tion taken on the dotted line IV—IV of Fig. 3. Fig. 5, is a detail perspective view of the rock-frame of the controlling mechanism. Fig. 6, is a detail perspective view of one of the clutch-members of such mechanism. Fig. 7, is a plan view of the clutch sleeve forming a part of the mechanism. Fig. 8, is an end view of the same. Fig. 9, is a view partly in section and partly in elevation of a 60 spiral gear forming a part of the mechanism. Fig. 10, is a horizontal section of a spiral gear provided with a cam groove for reciprocating the sliding clutch-members of the mechanism. Fig. 11, is a detail perspective view of 65 a traveling cross-head clutch-member used in conjunction with the mechanism. Fig. 12, is a detail perspective view of a clutch collar for use in connection with the cross-head clutch-member. Fig. 13, is a detail perspective view of a modified form of controlling 70 mechanism. Fig. 14, is a central vertical section of the same. Fig. 15, is a detail perspective view of the clutch sleeve forming a 75 part of the modified construction of the 80 mechanism.

In the said drawings, 1 indicates a cast-metal base of suitable size and form, and 2, 3, a pair of bearing standards formed thereon, standard 3 being formed with a semi-circular casing 4, which in conjunction with the cap 5 provides a chamber for a worm gear, not shown, mounted rigidly on shaft 6, journaled in said standards and provided at one end with a thread 7 and between the 85 standards with a winding drum 8, for the usual cable for raising and lowering the car.

9 indicates a cylindrical casing underlying the worm-gear-casing and forming a part of standard 3 and adapted to contain the 95 threaded end, not shown, of and form a bearing for the longitudinal shaft 10, the threaded end meshing as usual in this class of machinery, with the worm gear hereinbefore referred to. The shaft 10 is the armature 100 shaft of a suitable electric motor 11, having the customary switch 12 mounted on the rheostat box 13, the rotatable arms 14 (one only appearing) being connected in a well-known manner to move with the bevel pinion 15, to which motion is imparted by the mutilated bevel gear 16, secured on shaft 17, journaled at one end in a bearing 18 secured to the rheostat box and in a pair of bearing brackets 19 secured to the cap 5, it being understood that when the shaft is rotated in 105 one direction or the other it causes the arm 110

14 shown in dotted lines behind shaft 17 in Fig. 1, to engage the upper or lower contact terminal of switch 12.

A rock frame journaled on shaft 17 between bearings 19, and of oblong rectangular form in plan view, comprises ends 20 and sides 21, the latter being of reduced width centrally as at 22, and provided at opposite sides of such reduced portions with substantially L-shaped slots 23 and 24, the slots 23 being inverted with respect to each other, the same being true of slots 24. One end wall is provided with curved hooks 25 at opposite sides of its axis and between said hooks and above said axis is a bolt 26, and a clamping plate 27 to be clamped by said bolt against the said end wall, and the clamping plate and end wall are formed with registering grooves to provide an opening 28, for a purpose which hereinafter appears.

29 indicates a sleeve secured rigidly on shaft 17 centrally of the rock frame and provided at one end with outwardly projecting clutch lugs 30 and at the other with similar lugs 31. It is also formed near the last-named end with a collar 32 provided with a clutch lug 33 and secured upon said sleeve near the other end by a set screw 34 is a collar 35.

36 is a spiral gear journaled on sleeve 29 between collars 32 and 35 and provided with a notch 37 receiving the clutch lug 33 and capable of a certain amount of rotatable movement before either end wall of such notch comes into engagement with said lug 33.

38, 38^a indicate a pair of slidable clutch-members journaled on shaft 17 within the rock frame at opposite ends of sleeve 29 and provided at their outer ends with annular grooves 39 and at their inner ends with clutch lugs 40, the clutch lugs 40 of one of the slideable clutch-members being adapted to interlock with lugs 30 of the sleeve and the clutch lugs 40 of the other slideable clutch-member 45 being adapted to interlock with the lugs 31 at the opposite end of said sleeve, and projecting radially outward from and at diametrically opposite points on sides of each clutch-member are wings 41, the wings of one clutch-member standing normally at an angle to the wings of the other. The wings of clutch-member 38 normally occupy the vertical portions of slots 23 of the rock-frame and the wings of clutch-member 38^a normally occupy the vertical portions of slots 24 of said rock-frame.

42 indicates a pair of clutch levers connected in the usual manner with clutch-members 38 and 38^a so as to reciprocate the latter without interfering with their rotative movement, the lower ends of said levers being pivoted at 43 to lugs projecting from the base. The clutch levers are provided with outwardly projecting pins 44, see Fig. 10, engaging the slots 46, 47 of a spiral gear 45

meshing with spiral gear 36, each of said slots extending for about one hundred and eighty degrees with the former of greater diameter than and communicating with the latter, cam shoulders 48 being formed at the points of connection of the slots, the inner and outer parts of the wheel being connected by bridge portions 49, at the opposite side of wheel from the levers 42.

50 indicates a chain or cable rigidly secured at its upper end to the hub of wheel 45 and equipped with a weight 51 for a purpose which hereinafter appears, said weight being mounted slidingly on the vertical arm of a bracket 52 secured to the base in any suitable manner. A rock frame or yoke comprises an end bar 53 cast or otherwise secured to the hub of wheel 45 and an inverted-U-shaped frame 54, journaled on the shaft 6 and bolted to bar 53.

55 is a traveling cross-head having a threaded opening 56 engaged by screw 7 and provided at the opposite sides of said opening with clutch lugs 57 and 58 for engagement respectively with the teeth of a pair of clutch collars 59 and 60, secured by set screws 61 and 62 respectively on shaft 7, the distance between the clutch collars determining the extreme limit of travel of the elevator car.

63 and 64 indicate cables fitting at corresponding ends in the curved hooks 25 of the rock frame on shaft 17 and fitting and clamped in the opening 28 formed by and between the corresponding end of said rock-frame and the clamping plate 27. The cables 63 and 64 depend from said rock frame and are looped respectively around the sheaves 66 and 67 journaled on brackets 68 secured at the bottom of the elevator shaft, the cables also extending around sheaves, not shown, at the top of the elevator car, thence down around sheaves 69 mounted on a rocker arm 70 of the elevator lever 71, and thence up to the top of the elevator shaft and over another set of sheaves, not shown, and down to a sliding weight also not shown, the particular arrangement of the cables, except the attachment and guiding means for their lower ends shown in Fig. 2, being illustrated and described in the patent to A. and F. E. Turner, controlling device for elevators, #493,607, March 14, 1893.

72 indicates a suitable brake mechanism to control the motor shaft and 73 a lever carried by the core of the solenoid 74 in circuit with the motor, the energization of the solenoid holding the lever elevated and the brake mechanism inoperative, a spring, not shown, being adapted to throw the brake mechanism into operative relation with the motor shaft when the circuit is broken through the motor. To this special brake mechanism no claim is made and it is therefore shown only in Fig. 1.

75 indicates a lever pivoted to standard 3

at 76, and equipped at one side of said pivot with a weight 77 to hold the opposite end of the lever close to the bottom of the drum, in order that the drum cable, not shown, in the 5 event that it becomes slack, shall depress said lever and raise its weighted end and withdraw it from the path of an upright lever 78 pivoted at 79 to an arm of standard 3 and at its upper end engaging a clutch 10 collar 80 mounted to slide but not turn on the drum shaft, a retractile spring 81, normally under tension, connecting the lever 78 with a part of standard 3 for the purpose of throwing the slideable clutch-member 80 into engagement with the clutch face 82 of the 15 spiral gear 45, for a purpose which herein-after appears.

In practice the parts are normally disposed as shown in the drawings, that is to say the 20 rock frame is horizontal and its reduced portions 22 are disposed centrally within the slots 83 of gear 36, the lever of the car being also in its neutral or vertical position. To start the car, the operator swings the lever 25 71 to one side and thus through the instrumentality of the cables rocks the rock frame, this action through its engagement with the wings of the clutch-member 38 turns said clutch-member and through the connection of the 30 same with the clutch sleeve turning the latter and consequently closing the switch and completing a circuit through the motor, the completion of said circuit effecting the energization of the solenoid and hence the release by 35 the brake mechanism of the motor shaft.

The operation of the motor through the instrumentality of the connections described, 40 operates the drum and moves the elevator up or down according to the rotation of the drum shaft, incidentally causing its cross-head 55 to travel outward or inward as the case may be on the threaded portion of said shaft, it being further noted in this connection that the other clutch-member 38^a 45 through its engagement with the opposite end of the clutch sleeve, is turned by the latter so as to maintain its same relative position with the rock-frame, the movement of said last-named clutch-member being of course an inoperative movement, that is to 50 say, a movement which does not affect the position of any other part. To arrest the elevator, the operator pulls lever 71 back to its initial or vertical position and in so doing 55 rocks the rock-frame back to its horizontal position, the rock-frame by engagement with the wings of the last-named clutch-member 60 rocking the latter back to its initial position and causing it through its engagement with the clutch sleeve to turn the shaft 17 back to its original position and therefore break the 65 circuit through the motor and solenoid to permit the brake mechanism to arrest the motor shaft and hence the drum and elevator car, it being noted in this connection, that as

the return movement of the rock-frame takes place, the clutch-member first referred to is turned to its original position through its engagement with the adjacent end of the clutch-sleeve, this return movement of said first-named clutch-member being an inoperative movement in the sense that the first movement of the companion clutch-member was inoperative, that is to say both of said movements are simply to position the clutch-members for subsequent operative movements.

With each starting and stopping movement of the elevator the above operations occur, it being of course understood that to reverse the travel of the elevator the lever is manipulated to reverse the rock-frame action, and hence the clutch-member which originally was moved to position for a subsequent operative action, performs a definite operative function on its first movement 85 while the first movement of the other clutch-member is simply to position it for operative action on its subsequent movement.

Assuming that the operator from any cause, fails to arrest the elevator when it 90 attains a predetermined limit of travel, the outward or inward movement, as the case may be, of the cross-head, continues until said cross-head comes within the sphere of action of a clutch collar on the drum shaft, 95 and is therefore turned by the latter, this turning movement of the cross-head likewise turning the yoke and spiral gear 45 and also effecting the elevation of the weight 51. The operation of gear 45 imparts operation 100 to the intermeshing gear 36, and at the same time one of the levers 42 is thrown outward by the engagement of its pin 44 with the upwardly moving cam shoulder 48, the cam shoulder forcing said lever outward until 105 its pin engages the slot 46, the pin of the companion lever remaining in slot 47. It will thus be seen that the clutch-member connected to the last-named lever is not moved longitudinally upon the shaft but 110 that the clutch-member connected to the other lever is moved longitudinally upon the shaft until disengaged from the clutch sleeve 115 29, this engagement taking place as the spiral gear 36 starts to turn and before the approaching end of the notch 37 of said gear comes into engagement with the tooth 33 of the clutch-sleeve, it being also understood in this connection that when said clutch-member has moved outward as explained, its wings 120 enter the portions of the slots of the rock frame extending parallel with shaft 17. The gear 36 by the engagement of said end-wall of its notch with tooth 33 turns the sleeve 29 and hence shaft 17 to open the circuit and 125 effect the arrest of the elevator car in the manner hereinbefore explained, it being noticed in this connection that the clutch-member which was not moved by its lever is turned through its engagement with the 130

clutch sleeve to dispose its wings at opposite ends of the upright portions of the slots of the rock-frame. As the elevator car is thus arrested, it will be apparent that the clutch-member which was moved by its lever 42, does not turn with the clutch sleeve and hence is disposed out of alinement therewith that is to say, its teeth are out of alinement with the notches of the clutch-sleeve. To restore said parts to operative relation, the operator must return lever 71 to its original or vertical position and through the instrumentality of the ropes or cables 63 and 64 rock the rock-frame, this action, because the wings are engaged with the longitudinal portions of the slots of said frame, rocking the last-named clutch-member back into alinement with the clutch-sleeve without disturbing the companion clutch-member and the clutch-sleeve and shaft. He then swings the lever to the opposite side of its pivot and thereby rocks the rock-frame and the clutch-members 38 and 38^a and hence the clutch-sleeve and shaft 17, this action resulting in the operation of the switch and again completing the circuit through the motor to cause the same to release the brake and operate the drum and thus move the elevator downward or upward as the case may be. As the movement of the drum is thus reversed the clutch collar 59 or 60 revolves so as to release the cross head 55 and thus permit the elevated weight 51 to gravitate and turn the gear 45 and incidentally the yoke and cross-head back to their original positions, the revolution of said gear through one of its cams swinging inward the lever 42 connected to the disengaged clutch-member to effect the reengagement of said clutch-member with the clutch-sleeve and the disengagement of its wings from the portions of the slots of the rock-frame extending parallel to the axis thereof, it being obvious that gear 36 is revolved back to its original position by the descent of the weight. In the movement of the clutch-member which results in the disengagement of its wings from the portions of the slots referred to, said wings remain in the path of backward or return movement of the rock-frame in order that when the lever is brought back to vertical position, the incidental movement of the rock-frame will cause the last-named clutch-member, through the instrumentality of the clutch-sleeve, to operate the shaft 17 and therefore break the circuit and effect the stoppage of the car, with all of the parts in the positions initially occupied and therefore ready for another lever movement to start the car either upward or downward.

With the construction shown in Figs. 13 to 15 inclusive, the operation is precisely the same as that described, but it will be noticed by reference to said figures and the following description that the rock frame is

capable of a greater range of movement with respect to the spiral gear because it is outside of the latter instead of extending through it, it being further noticed that in the construction shown by the said figures, the clutch levers 70 will be at the opposite ends of the rock-frame and consequently can never be struck by the latter in its rotary movement as might occur in the construction shown by the preceding figures. By giving the rock-frame a more extended rotary movement, its leverage on the switch-operating shaft is increased a slight sacrifice of speed, the operation of the switch-operating shaft at less speed being sometimes desirable. 80

Referring specifically to the construction embodied in Figs. 13 to 15 inclusive, 17 indicates the switch-operating shaft, 84 is a clutch-sleeve corresponding to clutch-sleeve 29 of Figs. 7 and 8 and like the latter provided with end teeth, 85 and 86, and a tooth 87. 36 is the spiral gear mounted upon the clutch-sleeve and provided with a notch 88 corresponding to notch 37 and receiving the tooth 87. 38 and 38^a indicate the pair of clutch-members mounted slidably and rotatably on shaft 17. The rock-frame is constructed as follows: 89 is a pair of collars journaled on the clutch-members 38 and 38^a and secured at their inner ends to plates 90 journaled upon the clutch-sleeve 84 and gear 36 and provided with upwardly projecting arms 91, equipped with inwardly projecting lugs 92, through which bolts 93 extend to secure them rigidly together. 100 The collars 89 are provided at their inner ends with slots 94 to receive the wings 41 of the slideable clutch-members, and projecting inwardly from the base of each slot 94 is an arm 95 to provide communicating laterally-extending slots 96 for the reception of said wings when the rock-frame is to be interlocked as regards rotary movement, with one of the slideable clutch-members. 97 is a flanged wheel secured to one of the collars 89 and adapted for the reception of the cable or cables 63, the cables being adapted to be fastened to the wheel in any suitable manner so that when moved by the lever in the car or cage, the wheel and consequently the 115 rock-frame constituted by the collars and plates 90 will be rocked. With this construction as hereinbefore stated the rock-frame has a wider range of rotatable action than the rock-frame shown most clearly in Figs. 3, 4, and 5, it being also noticed that the grooved ends of the slideable clutch-members are beyond the ends of the rock-frame so that the latter can in no event come into contact with the clutch-reciprocating levers. 120 125

From the above description it will be apparent that I have produced an elevator-controlling mechanism possessing the features of advantage enumerated as desirable and I wish it to be understood that I do not 130

desire to be restricted to the exact details of construction shown and described as obvious modifications will occur to one skilled in the art.

5 Having thus described the invention what I claim as new and desire to secure by Letters-Patent, is —

1. The combination with an electric elevator car or cab and its controlling switch, 10 of a manually-operated device on the car, mechanical switch-operating means, mechanical connections between said means and the device on the car whereby the latter may effect movement of the former and the switch, and mechanical means for automatically throwing said switch-operating means to such position with respect to the said device on the car that the operation of the latter to neutral position shall not affect 15 the position of said switch-operating means.

2. The combination with an electric elevator car and its controlling switch, of a clutch-member movable always with the switch, a companion clutch-member interlocked with the first-named clutch-member, means on the car connected to said companion clutch-member to turn the same and hence the first-named clutch-member and the switch, and means for automatically 25 disengaging the members of the clutch at predetermined points in the travel of the car.

3. The combination of a hoisting engine and its controlling mechanism, of a shaft journaled on said engine, a clutch-sleeve 30 secured on said shaft so as to revolve with it, sliding clutch-members arranged to engage with said clutch-sleeve and journaled on said shaft; means for operating said sliding clutch-members alternately along said shaft 35 and into and out of engagement with said clutch-sleeve, a gear wheel journaled on said clutch-sleeve and arranged to rotate it independent of said sliding clutch-members, a second gear wheel meshing with the first and 40 provided with cams to operate said sliding clutch-members, and a rock-frame suitably journaled and arranged to operate the said sliding clutches independently of the gear wheels.

4. The combination of a shaft, a clutch-member movable therewith, a pair of clutch-members movable endwise and also rotatably, a rock-frame suitably journaled and connected to the said pair of clutch-members, 50 and means to rock the rock-frame and cause it to move one of the pair of clutch-members and therefore turn the first-named clutch-member and the shaft and the other of the pair of clutch-members.

5. The combination of a shaft, a clutch-member movable therewith, a pair of clutch-members movable endwise and also rotatably, a rock-frame suitably journaled and connected to said pair of clutch-members, 55 means to rock the rock-frame and cause it to

move one of the pair of clutch-members and therefore turn the first-named clutch-member and the shaft and the other of the pair of clutch-members, means to withdraw the endwise-movable clutch-member which was 70 caused by the rock-frame to move the first-named clutch-member, out of engagement with the latter and into interlocked relation with the rock-frame as regards rotary movement.

6. The combination of a shaft, a clutch-member movable therewith, a pair of clutch-members movable endwise and also rotatably, a rock-frame suitably journaled and connected to said pair of clutch-members, means 75 to withdraw the endwise-movable clutch-member which was caused by the rock-frame to move the first-named clutch-member, out of engagement with the latter and into interlocked relation with the rock-frame as regards rotary movement, and 80 means to rock the first-named clutch-member and thereby turn the shaft in a reverse direction from one of its normal stationary positions and the endwise-movable clutch-member in engagement with said shaft without affecting the position of the rock-frame and the clutch-member interlocked therewith as regards rotary movement.

7. The combination of a shaft, a clutch-member movable therewith, a pair of clutch-members movable endwise and also rotatably, a rock-frame suitably journaled and connected to said pair of clutch-members, means to rock the rock-frame and cause it to move one of the pair of clutch-members and 100 therefore turn the first-named clutch-member and the shaft and the other of the pair of clutch-members, means to withdraw the endwise-movable clutch-member which was caused by the rock-frame to move the first-named clutch-member, out of engagement with the latter and into interlocked relation with the rock-frame as regards rotary movement, means to rock the first-named clutch-member and thereby turn the shaft in a reverse direction from one of its normal stationary positions and the endwise-movable clutch-member in engagement with said shaft without affecting the position of the rock-frame and the clutch-member interlocked therewith as regards rotary movement, 105 and means to yieldingly resist the said reverse operation of the shaft and after the movement of the rock-frame has been reversed effect the reengagement of the disengaged clutch-member with the first-named clutch-member and its disengagement as regards rotary movement in one direction, 110 from the rock-frame.

8. In an apparatus of the character de- 130

- scribed, the combination with a hoisting engine and its controlling mechanism, of a shaft to operate said controlling mechanism, a clutch-member rotatable with said shaft, a 45
5 pair of journaled and slidable clutch-members engaging the first-named clutch-member, means to rock one of said pair of slidable clutch-members and cause it to turn the first-named clutch-member, the shaft and 50
10 the companion slidable clutch-member, means to withdraw the slidable clutch-member which was caused to turn the first-named clutch-member, from engagement with the latter, and means to rock the first-named 55
15 clutch-member and thereby turn the shaft in a reverse direction from one of its normal stationary positions and the endwise-movable clutch-member in engagement with 60
said shaft.
10 9. In an apparatus of the character described, the combination with a hoisting engine and its controlling mechanism, of a shaft to operate said controlling mechanism; a clutch-member rigid with said shaft; a 65
25 pair of journaled and slidable clutch-members engaging the first-named clutch-member, either of said pair of clutch-members being capable of turning to effect turning movement of the first-named clutch-member, the 70
30 shaft and the companion slidable clutch-member; means to withdraw the slidable clutch-member which may be employed in turning the first-named clutch-member, from engagement with the latter after it has 75
35 turned the same; means to rock the rigid clutch-member and thereby turn the shaft in a reverse direction from one of its normal stationary positions and the slidable clutch-member in engagement with said shaft and 80
40 movable means to turn in one direction and cause one of said slidable clutch-members to turn the rigid clutch-member, the shaft and the companion slidable clutch-member and after such movement, be capable of moving
in another direction, to redispose the withdrawn slidable clutch-member in position to be slid into reengagement with the clutch-member rigid with the shaft.
10. In an apparatus of the character described, the combination of a shaft, a clutch-sleeve rigidly secured thereon, a gear wheel adapted to turn with the clutch-sleeve and also have a limited independent rotative movement, slidable clutch-members journaled on the shaft and normally interlocked with the clutch-sleeve and provided with wings, a rock-frame journaled on the shaft and provided with substantially L-shaped slots having their upright portions normally engaged by said wings, a gear wheel meshing with the first-named gear wheel and provided with a pair of concentric slots of different radius and with cam shoulders at the junction of said slots, levers having pins normally engaging one of said slots and connected to reciprocate without interfering with the rotatable action of the slidable clutch-members, a driven shaft forming a journal for the second gear wheel and provided with a threaded portion, clutch collars rigidly secured on the threaded portion of said shaft, a yoke movable with the second gear wheel and surrounding said collars, a cross-head engaging the threaded portion of the shaft and guided to reciprocate thereon between the clutch collars, by said yoke, and a weight connected to be raised by movement imparted to the yoke by one of the clutch collars and to reverse the action of the yoke when the cross-head is disengaged from the engaging clutch collar.

In testimony whereof I affix my signature, in the presence of two witnesses.

FREDERICK E. TURNER.
